(57) **CLAIM**

The ornamental design for smoke detector cover for fire alarm, as shown and described.

DESCRIPTION

FIG. 1 is a front top perspective view of a smoke detector cover for fire alarm.

FIG. 2 is a rear bottom perspective view thereof.

FIG. 3 is a top plan view thereof.

FIG. 4 is a bottom plan view thereof.

FIG. 5 is a front elevation view thereof.

FIG. 6 is a rear elevation view thereof.

FIG. 7 is a left side elevation view thereof; and,

FIG. 8 is a right side elevation view thereof.

The dash-dot-dash lines demarcate the claim boundary beyond which no claim is made.
